UNITED STATES PATENT OFFICE.

ANTON M. VEDOE, OF QUINCY, MASSACHUSETTS.

REAMER.

Application filed January 21, 1921. Serial No. 439,016.

To all whom it may concern:

Be it known that I, ANTON M. VEDOE, a subject of the King of Sweden, residing at Quincy, in the county of Norfolk and State of Massachusetts, have invented an Improvement in Reamers, of which the following description, in connection with the accompanying drawings, is a specification, like characters on the drawings representing like parts.

This invention relates to reamers, and more particularly to reamer attachments for guiding a reamer during the reaming operation.

15 Heretofore, difficulty has been experienced in retaining a reamer in its proper position of alignment throughout the reaming operation, since the force exerted upon an end of the reamer to turn the same often tends to cant the reamer in the hole being reamed.

20 The primary object of the present invention, therefore, is to provide attachments for reamers that will maintain the reamers in the desired position of alignment throughout the reaming operation; and the attachments are designed more particularly for reamers used in reaming out aligned holes or bearings.

25 In various mechanical constructions it is desired to provide spaced journal boxes or bearings that are aligned, and are reamed accurately to size throughout the bearing seats. The present invention contemplates utilizing one of the spaced bearings to hold the reamer in proper position of alignment while the other bearing or bearings are being reamed.

30 The reamer attachments are preferably so constructed that they may be readily applied to reamers heretofore manufactured, but obviously reamers may be manufactured having certain features of the present invention embodied therein as an integral part of the reamer.

35 The above and other features of the invention will be clear from the following description in connection with the accompanying drawings which show one good practical form of the invention.

In the drawings:

Fig. 1 is a side view of a type of reamer heretofore used;

Fig. 2 is a sectional view through the 55 reamer of Fig. 1;

Figs. 3, 4 and 5 are side views of attachments for the reamer shown in Fig. 1, the parts being shown disassembled in Figs. 4 and 5;

Fig. 6 is an end view of a split sleeve;

Fig. 7 is a side view of the reamer showing the use of one attachment therefor; and

Fig. 8 is a side view of the reamer showing the use of another attachment therefor.

The reamer attachments forming the subject-matter of this invention may be variously constructed and may be applied to different types of reamer, but it is herein illustrated as applied to a well known type 70 of expandible reamer designated in its entirety by 10 and best shown in Fig. 1.

The reamer 10 is shown as provided with a cylindrical body portion 11, at the opposite ends of which are provided the threaded portions 12 and 13, and slots are formed longitudinally of said portions to receive the adjustable reamer blades 14. The bottom of the slots are usually tapered slightly and the cooperating edge of the blades are 80 correspondingly tapered to effect expansion of the blades upon adjusting them longitudinally of the body. The blades are shown as adjustably secured in place in a well known manner by the nuts 15 and 16, 85 each having an end undercut to receive the correspondingly shaped ends of the blades 14. The reamer 10 is shown as having the usual shank 17.

The construction of the reamer attachments may be varied in accordance with the different types of reamers with which it is to be used, and also to meet the different conditions under which it may be used, and it may be desirable under some conditions 90 to provide the reamer with means at its forward end to guide the same in its reaming operation, while under other conditions it may be desirable to guide the reamer from a position to the rear of its cutting surface. Accordingly, in Fig. 7 the reamer is shown as guided into the hole to be reamed from a position in front of the cutting portion of the reamer, while in Fig. 8 the reamer is shown as entering one hole while 100 it is guided from a second hole to the rear of the cutting portion of the reamer.

One of the uses for which the present invention is well adapted is in connection with the piston of an internal com- 110

bustion engine to ream out the bushings in which the wristpin for the crank shaft is journaled. In Fig. 7 a well known type of internal combustion engine piston is designated by 18. This piston has inwardly projecting bosses 19 in which are mounted the bushings 20. The bushings 20 are usually driven tightly into the bosses 19 and are then reamed out, but difficulty has been experienced heretofore in maintaining the reamer in its proper position of alignment as it enters one of the bushings.

In accordance with the present invention this difficulty is done away with by providing an expandible sleeve 21 within the left hand bushing 20 of Fig. 7 which acts through the extension 22 to guide the reamer. This construction maintains the reamer in the desired position of alignment as it enters the right hand bush 20, and as a result the bushing is reamed to a uniform diameter throughout its length.

In the embodiment illustrated the extension 22 has a sleeve portion 23 internally threaded as at 24 and a reduced portion forming a pin 25. The construction is such that when the extension is to be applied to the type of reamer shown in Fig. 1, the nut 15 may be removed and the extension 22 screwed on the threaded portion 12 in place of the nut. The expandible sleeve 21 may be variously constructed and may be made a part of the extension 22 or separate therefrom. In the present instance the sleeve 21 comprises an elongated collar 26 having an internal bore 27 to slidably receive the reduced portion or pin 25 of the extension, and at one end of the collar is formed the tapered shoulder 28 while a nut 29 is threaded upon the other end of the collar and has a similar tapered shoulder 30. A split cylinder 31 is mounted upon the collar 26 with its ends engaging the tapered shoulders 28, 30, and the cylinder is expanded by tightening up the nut 29. The outer surface of the nut 29 is preferably knurled, as is also the opposite end of the collar 26.

The expansion sleeve 21 may be readily expanded to fit snugly within one of the bushings 20, where it will serve to guide the reamer as it enters the other bushing, and the expandible sleeve may be pushed forward by the reamer as it travels through the bushing in the reaming operation.

When the aligned bushings are relatively close to each other as in Fig. 7, it is unnecessary to provide a guiding bushing at the rear of the cutting portion of the reamer, as the reamer will enter one bushing before it clears the other, but if the bushings or holes to be reamed are spaced apart a distance greater than the length of the cut-

ting face of the reamer, as is the case in Fig. 8, a rear expandible sleeve 32 is preferably provided. The expandible sleeve 32 may be constructed similar to the expandible sleeve 21, except that the collar 33 is preferably internally threaded as at 34 to be screwed on the threader portion 13 of the reamer. The split cylinder 35 is expanded similar to the split cylinder 31. In Fig. 8, 36 and 37 designate space plates or like having aligned holes therein that are to be reamed, and in reaming these holes the guiding mechanism of Fig. 7 as well as that of Fig. 8 is preferably used, the nuts 15 and 16 being replaced by the attachments. In reaming the spaced plates 36 and 37, the forward guiding mechanism of Fig. 7 will engage the bore of the plate 36 and guide the reamer as it enters the bore of plate 37, and the rear expandible sleeve 32 will engage the bore of the plate 37 and guide the reamer as it enters the bore of the plate 36.

The present invention may be given various embodiments other than herein disclosed without departing from the full scope of the same as defined by the claims.

What is claimed is:—

1. An expandible reamer and guides for guiding the reamer in reaming aligned holes, comprising in combination, a reamer body threaded at its ends to receive blade holding means, reamer blades mounted upon the reamer body for adjustment longitudinally of said body, a collar having threaded engagement with one threaded end of the reamer body and adapted to secure one end of the reamer blades in place, an expandible sleeve mounted on said collar, an extension having threaded engagement with the other threaded end of the body and adapted to secure the other end of the reamer blades in place, and an expansion sleeve fitted upon said extension.

2. An expandible reamer and guides for guiding the reamer in reaming aligned holes, comprising in combination, a reamer body threaded at its ends to receive blade holding means, reamer blades mounted upon the reamer body for adjustment longitudinally of said body and the blades and body having cooperating inclined surfaces for expanding the blades as they are forced longitudinally of the body, a collar having threaded engagement with the rear threaded end of the reamer body and adapted to secure the rear ends of the reamer blades in place, an expandible sleeve upon said collar, an extension at the forward end of the reamer body, and an expansion sleeve fitted upon said extension.

3. An expansion reamer and guide for

guiding the reamer in reaming aligned holes, comprising in combination, a reamer body provided with expansible reamer blades, means for expanding said blades, an extension projecting from the forward end of the reamer body, an elongated collar fitted

on said extension, a cylinder surrounding said collar, and means for expanding the cylinder.

In testimony whereof, I have signed my **10** name to this specification.

ANTON M. VEDOE.
